EXCESSIVE SPEED RESPONSIVE ENGINE
GOVERNORS

Robert E. Young, Anderson, and Clarence L. Julian,
Middletown, Ind., assignors to General Motors Corporation,
Detroit, Mich., a corporation of Delaware
Filed Jan. 3, 1964, Ser. No. 335,490
2 Claims. (Cl. 137—57)

This invention relates to engine governors and more particularly to the type of speed control for an internal combustion engine employing a fluid operated servomotor for actuating a governor throttle.

It is common to provide internal combustion engines with a speed governor in situations where it is desirable to limit the maximum speed of the engine. Such governors are usually adjustable to govern the engine over a wide range of predetermined speeds and will function effectively throughout the governing range. A governor of this type is shown in the United States Patent 2,664,867 issued Jan. 5, 1954, to the assignee of the present invention.

This type of speed governor usually employs a centrifugally unbalanced valve slidable in a transverse bore in the ignition distributor shaft of the engine. The valve is in a more or less constant state of motion when the engine is running and operates to restrict the air bleed to the servomotor controlling the governor throttle. When a large or sudden engine load decrease occurs, this causes overtravel of the valve to the closed position suddenly cutting off air to the servomotor. To reduce the hunting condition and the overtravel effect at sudden high speed, the centrifugal valve may be provided with a subsidiary air bypass passage.

This construction is the subject of United States Patent 2,828,725 issued Apr. 1, 1958, also to the assignee of the present invention.

Experience has shown that a centrifugal governor valve mounted directly in the distributor shaft is subject to wear after long periods of time due to the hunting motion which is a condition of its environment. When wear occurs, the variable area bleed orifice restricted by the valve element tends to permit air leakage resulting in a change in the governed speed.

In the improved governor of the present invention, the speed responsive mechanism of the governor is not integral with the governor valve thus doing away with some of the objectionable features of the centrifugally activated integral valve. In the present arrangement, a governor shaft carries a speed responsive unit acting independently to move the governor valve according to the engine speed to control the servomotor and the position of the governor throttle.

A more detailed understanding of the invention may be had by referring to the following description and drawings wherein:

FIGURE 1 is an elevation view of the air cleaner and ignition distributor areas for an internal combustion engine incorporating the invention;

FIGURE 2 is an enlarged offset sectional view of the governor mechanism shown in FIGURE 1.

Referring to FIGURE 1, a carburetor 10 is mounted on the engine intake manifold 12 through an intermediate governor duct 14 and carries an air cleaner 16. A butterfly throttle valve 18 is supported in a carburetor barrel by a shaft 20 to determine fuel-air flow to the engine below the governed speed in accordance with the position of the manual throttle control 22. An air balanced governor throttle valve 24 is supported in the governor duct 14 by shaft 26 to determine fuel-air flow to the engine in accordance with the engine load to maintain the engine at a predetermined governed speed when

the carburetor throttle valve 18 is sufficiently opened for the engine governor to assume control.

Referring to FIGURE 2, actuation of the governor throttle 24 is accomplished by servomotor 28 which is supported on a column 30 and connects with a crank-arm 32 of the throttle valve. The servomotor 28 includes a cylinder 34 forming a collapsible chamber 36 with a flexible diaphragm 38 which carries a link 40 pivotally connected to the crankarm 32 and biased to the governor valve opening position by a tension spring 42 connected between the crankarm 32 and a lug 44 within the governor throttle housing 45. The spring force may be varied by hooking the spring on other lugs 44 thus increasing the tension and making it harder for the servomotor to close the governor valve.

A passage 46 formed in the column 30 connects the collapsible chamber 36 to the governor duct 14 on the engine side of the governor throttle valve. A conduit 48 also connects with the chamber 36 and to atmosphere by way of the air cleaner 16 through the speed sensing unit 50 and air bleed conduit 52.

The unit 50 is mounted directly on the distributor housing 54 carrying the ignition distributor shaft 55 and includes a body portion 57 having a bore 58 extending longitudinally therethrough and transversely to the axis of the distributor shaft 55. A governor shaft 60 is journaled at one end of the bore 58 in a coupling and cross shaft bearing unit 62 and at the other in antifriction bearing 64. It is driven at some speed proportional to that of engine speed through the helical gear transmission arrangement 65. The bore 58 is closed at one end by the plate 67 having a central aperture 68 through which one end of the governor shaft 60 extends. A splined portion 70 on the governor shaft beyond the plate 67 carries a yoke element 71 and fly ball weight 72 which rotate with the governor shaft. The centrifugally acting weight 72 is pivoted at 73 on the yoke element which includes a wing portion 74 opposite the weight to act as a counterbalancing mass. A finger 75 integrally formed on the weight 72 extends radially inwardly to a point in alignment with the governor shaft. The end of the governor shaft is formed with a sleeve portion 76 having an axial slot 78 through which passes the end of the finger 75. A plunger 79 is slidably received in the sleeve portion 76 in front of the finger 75.

A cover member 80 for the unit 50 seals with the body portion 57 and includes a head portion 81 having an elongated bore 82 therein aligned with the governor shaft 60. Transverse passages 83 and 84 intersecting with bore 82 are adapted to threadably receive fittings on the air bleed conduit 52 leading to the air cleaner 16 and on the conduit 48 leading to the vacuum servomotor 28. Passage 83 terminates in an orifice 85 substantially larger than the air bleed orifice 86 of the passage 84.

A valve element 88 is slidably received in the bore 82 and is biased in the valve open position and against the end of plunger 79 by the spring 90. Adjustment screw 92 is provided to vary the biasing force applied by spring 90.

The valve 88 is provided to control the amount of air bleed to the vacuum servomotor 28 and thereby vary the position of the governor throttle valve 24. Air flow through the orifice 86 does not affect the valve 88 so that the movement of the valve is solely in accordance with engine speed.

With the engine under governor control, the valve 88 decreases air bleed to the servomotor 28 on momentary engine acceleration due to a falling load thereby occasioning increased vacuum in the servomotor chamber 36 which overbalances the spring 42 and moves the governor throttle valve 24 toward the closed position reducing

fuel-air flow to the engine to decelerate to governed speed. Conversely, the valve 88 increases air bleed on momentary engine decelerations due to an increased load thereby occasioning decreased vacuum to the servomotor chamber 36 which is overcome by the spring 42 tending to move the governor throttle valve 24 toward the opened position increasing fuel-air flow to the engine to accelerate the engine to governed speed.

The valve 88, in restricting the air bleed, never entirely closes the orifice 85; hence, as engine speed increases the valve moves to the right against the force of spring 90 in response to the push by the plunger 79 upon command of speed responsive weight 72. A limit stop 91 on the weight prevents overtravel. When the governed speed is reached, restriction of the orifice 86 by the valve takes place. Upon a large or sudden load decrease, overtravel of the valve 88 is minimized since it is not directly centrifugally unbalanced. Consequently, an air bleed bypass passage to minimize the effects of overtravel as in the above-mentioned Patent 2,828,725 is not considered necessary.

More importantly, the disadvantage with the centrifugally unbalanced valve mounted crosswise directly in the distributor shaft is the tendency to wear attendant with the constant hunting action of the valve in accordance with the centrifugal forces acting on it. The present valve arrangement is less subject to wear since the valve element is not sliding directly within the air bleed orifice.

While the preferred embodiment of the invention has been described fully in order to explain the principles of the invention, it is to be understood that modifications of structure may be made by the exercise of skill in the art without deviating from the intended scope of the invention as expressed in the appended claims.

What is claimed is:

1. A speed responsive centrifugal governor for an engine having a fluid pressure operated actuator, said governor comprising:

a housing adapted to be mounted on the engine;
a governor shaft rotatably carried by the housing and adapted to be driven at a speed proportional to engine speed, said shaft having a sleeve portion at one

end extending coaxially with the axis of rotation and an axially-directed slot in said sleeve portion; a yoke element rotatably carried by said governor shaft and pivotally supporting in centrifugally unbalanced flyweight having a finger extending through said slot into intersecting relation with the axis of rotation; said housing having a bore spaced from the yoke element and coaxial with the axis of rotation and a transverse passage intersecting the bore and communicating with the actuator;
a valve element slidably received in the bore, said valve element being movable in the bore to meter fluid flow through the passage;
and a plunger reciprocably carried in said sleeve portion and contacting both said finger and said valve element to provide an actuating connection therebetween, the contacts of said finger and plunger and of said plunger and valve element occurring substantially along said axis of rotation whereby frictional loss due to said contacts is minimized.

2. The device of claim 1 wherein said yoke element is splinedly connected to said governor shaft to permit ease of disassembly therefrom and said yoke element includes a wing portion oppositely disposed from the pivotally carried flyweight to balance the weight thereof.
